UNITED STATES PATENT OFFICE

JOSEF DORNBUSCH, OF CREFELD, GERMANY, ASSIGNOR TO THE ARTCOTE PAPERS, INC.,
OF IRVINGTON, NEW JERSEY

DESIGN FOR WALLPAPER OR SIMILAR ARTICLE

Application filed March 23, 1932. Serial No. 43,276. Term of patent 3½ years.

To all whom it may concern:

Be it known that JOSEF DORNBUSCH, a citizen of Germany, residing at Crefeld, in the State of Prussia, has invented a new, original and ornamental Design for Wallpaper or Similar Article, of which the following is a specification.

In the accompanying drawing:—

The figure is a surface view of a piece of wall paper or similar article showing the design. The area within the dot and dash lines represents one complete unit of the design.

I claim:—

The ornamental design for wall paper or similar article as shown and described.

In testimony whereof I affix my signature.

JOSEF DORNBUSCH.
